CLAIM

The ornamental design for a woman's shoe, as shown and described.

DESCRIPTION

FIG. 1 is a perspective view of a woman's shoe showing our new design;

FIG. 2 is a front end view thereof;

FIG. 2 is a front view thereof;

FIG. 3 is a back view thereof;

FIG. 4 is a right side view thereof;

FIG. 5 is a left side view thereof;

FIG. 6 is a top plan view thereof; and,

FIG. 7 is a bottom plan view thereof.

The broken line showing of sole and heel is included for the purpose of illustrating environmental structure and forms no part of the claimed design.

1 Claim, 6 Drawing Sheets
